[57] CLAIM

The ornamental design for toy building element, as
shown and described.

DESCRIPTION

FIG. 1 is a top perspective view of a toy building ele-
ment showing my new design;

FIG. 2 is a bottom perspective view thereof;

FIG. 3 is a top plan view thereof;

FIG. 4 is a bottom plan view thereof;

FIG. 5 is a front elevational view thereof; the rear ele-
vational view being identical, and

FIG. 6 is a side elevational view thereof; the side oppo-
site being identical.

FIG.1

FIG.2

FIG.5

FIG.3

FIG.6

FIG.4
